UNITED STATES PATENT OFFICE.

RONALD A. McCANN, OF SWISSVALE, PENNSYLVANIA, ASSIGNOR TO THE UNION
SWITCH & SIGNAL COMPANY, OF SWISSVALE, PENNSYLVANIA, A CORPOR-
ATION OF PENNSYLVANIA.

RAILWAY SIGNAL.

1,415,886.

Specification of Letters Patent.

Patented May 16, 1922.

Application filed November 13, 1919. Serial No. 337,642.

To all whom it may concern:

Be it known that I, RONALD A. McCANN, a citizen of the United States, residing at Swissvale, in the county of Allegheny and State of Pennsylvania, have invented certain new and useful Improvements in Railway Signals, of which the following is a specification.

My invention relates to railway signals, and particularly to signals of the type comprising a semaphore biased to the "stop" position, an electric motor for moving it to one or more proceed positions, and one or more electromagnets for operatively connecting the semaphore with the motor and for holding the semaphore in the position or positions to which it has been moved by the motor.

In signals of this character it is well understood that the energy required by the electromagnets is considerably greater while the semaphore is being moved by the motor than while the semaphore is being held in its proceed position or positions. One object of my invention is the provision of novel means for controlling the signal in such manner that a smaller amount of energy will be supplied to the electromagnet or electromagnets while the semaphore is being held in the proceed position than while the semaphore is being moved by the motor, thereby materially reducing the total amount of energy required for the operation of the signal.

I will describe several forms of apparatus embodying my invention and will then point out the novel features thereof in claims.

In the accompanying drawings, Fig. 1 is a view, partly diagrammatic, showing one form of signal which may be controlled in accordance with my invention. Fig. 2 is a diagrammatic view showing one form and arrangement of apparatus and circuits for the control of the signal shown in Fig. 1, and embodying my invention, the parts being shown in the positions corresponding to the stop position of the signal. Fig. 2^a is a view similar to Fig. 2, but showing the parts in the positions which they occupy when the signal indicates proceed. Fig. 3 is a diagrammatic view showing a modification of the apparatus and circuits shown in Fig. 2 and also embodying my invention, the parts being shown in the positions corresponding to the stop position of the sig-

nal. Fig. 3^a is a view similar to Fig. 3, but showing the parts in the positions which they occupy when the signal indicates proceed. Fig. 4 is a diagrammatic view showing another modification of the apparatus and circuits shown in Fig. 2, and also embodying my invention, the parts being shown in the positions which they occupy when the signal indicates stop. Fig. 4^a is a view similar to Fig. 4 but showing the parts in the positions which they occupy when the signal indicates proceed. Fig. 5 is a view showing a modification of the signal shown in Fig. 1. Fig. 6 is a diagrammatic view showing one arrangement of apparatus and circuits for the control of the signal shown in Fig. 5, the parts being shown in the positions which they occupy when the signal indicates stop. Fig. 6^a is a view similar to Fig. 6, but showing the parts in the positions which they occupy when the signal indicates proceed.

Similar reference characters refer to similar parts in each of the views.

Referring first to Fig. 1, the signal comprises a semaphore S pivotally mounted at point 2, and biased by gravity to the horizontal position in which it is shown in full lines and wherein the semaphore indicates "stop." This semaphore may be moved by the other apparatus shown in this view to an inclined position wherein it indicates "caution," and to a vertical position wherein it indicates "proceed," the two latter positions being shown in dash lines.

The mechanism for operating semaphore S comprises two arms A and A^a pivotally mounted at 3 and 3^a, respectively, which arms are biased to substantially the positions in which they are shown in the drawing. The arm A is at times moved upwardly around the point 3 as a center by means of a chain 6, which chain in turn is driven by an electric motor M. This chain is provided with rollers 11, which project laterally from the chain to engage with a fork 8, which is pivotally mounted in the arm A. This fork is controlled by an electromagnet H in such manner that when the magnet is energized the fork is held rigidly in the position shown with respect to arm A, that is, in a projected position in the path of the rollers 11; but that when the magnet is de-energized the fork is free to swing upwardly to a retracted position out

of the path of these rollers. When the arm A has been elevated by the chain 11, a shoulder 9 on the fork 8 engages with a latch 10 to hold the arm in the elevated position as long as magnet H is energized.

The arm A^a is controlled in a similar manner by a chain 6^a, which is also driven by the motor M, and by a latch 10^a. The various parts associated with the arm A^a are designated by the same reference characters as those associated with the arm A, but with the exponent "a" added in each instance.

Interposed between the arms A and A^a and the semaphore S is a rack and pinion device comprising a pinion 5 operatively connected with the semaphore, a rack 4 operatively connected with the arm A, and a rack 4^a operatively connected with the arm A^a. When the two operating arms are in their lower positions, both racks 4 and 4^a are in their lowest positions, so that roller 5 is likewise in its lowest position and the semaphore S is in the horizontal position wherein it indicates stop. If arm A is then raised by the chain 6, the consequent elevation of rack 4 causes pinion 5 to be raised to an intermediate position, and this pinion in turn moves the semaphore S upwardly to its inclined or caution position. If then the arm A^a is elevated, the consequent upward movement of the rack 4^a causes pinion 5 to be moved to its highest position and this in turn moves the semaphore S upwardly to its vertical or proceed position. When the semaphore indicates proceed, it is obvious that if the electromagnets H and H^a are de-energized, the two operating arms will drop to their lowest positions, so that the semaphore will return to its horizontal or stop position.

Referring now to Fig. 2, the reference character E designates the track rails of a railway track along which traffic normally moves in the direction indicated by the arrow. These rails are divided by insulated joints 13 to form a block section B-C, and this section is provided with a track circuit comprising a track battery 12 connected across the rails at the exit end of the section and a track relay T connected across the rails at the entrance end of the section. Located adjacent the entrance end of the section B-C is a railway signal which is similar to the signal shown in Fig. 1; in order to simplify the drawing, however, the only parts of this signal which are shown in Fig. 2 are the semaphore S, the motor M and the magnets H and H^a, together with certain circuit controllers which are operationally connected with the arms A and A^a in Fig. 1. This signal is controlled by a line relay R and a local relay L, these relays in turn being controlled by the track relay T and by a pole-changer P^a operated by a signal S^a which is located at the entrance

end of the block section to the right of point C.

As shown in Fig. 2, the block section B-C is occupied by a car or train which is represented by a pair of wheels and an axle W, so that track relay T is open. Relays R and L are likewise both open, so that magnets H and H^a are both de-energized and signal S consequently indicates stop. I will now assume that the car or train W passes out of block section B-C and into the section to the right of location C. Track relay T then closes, so that the line relay R becomes energized through the following circuit: from battery 53, through pole-changer P^a, wire 35, contact 36 of track relay T, wires 37 and 38, winding of relay R, wire 66, back contact 67 of relay L, wires 68 and 43, contact 44 of track relay T, wire 45, and pole-changer P^a to battery 53. Pole-changer P^a is then in such position that relay R is energized in what I will term the "reverse" direction, wherein its polarized contact 20 is open. Magnet H then becomes energized, the circuit being from battery D, through wires 14 and 54, front point of contact 15 of relay R, wire 16, magnet H, and wires 17 and 18 to battery D. It will be observed that at such time the entire voltage of battery D is applied to the terminals of magnet H, so that this magnet is strongly energized. Motor M is energized at the same time, the circuit being from battery D, through wires 14 and 54, front point of contact 15 of relay R, wires 19 and 23, contact 24, wire 25, motor M and wire 18 to battery D. Motor M then drives the chains 6 and 6^a, shown in Fig. 1, and inasmuch as magnet H is energized, arm A is moved to its elevated position, thus moving the semaphore S to its inclined or caution position. When this position is reached, contact 24 opens, so that motor M stops, but magnet H continues to be energized so that the semaphore is held in the caution position. When the semaphore reaches the caution position contact 31 closes.

I will now assume that the car or train passes out of the block section to the right of point C, so that signal S^a moves to the caution or to the proceed position, thereby reversing pole-changer P^a. This causes relay R to become energized in the opposite or normal direction, wherein the polarized contact 20 is closed. This does not affect the circuit for magnet H, but it closes a circuit for magnet H^a which circuit is from battery D, through wires 14 and 54, front point of contact 15, wires 19 and 19^a, polarized contact 20 of relay R, wires 21 and 27, back point of contact 28 of relay L, wire 29, magnet H^a, wire 30, contact 31, wire 32, back contact 33 of relay L, and wire 34 to battery D. The full voltage of battery D is then applied to the terminals of magnet H^a as

well as to magnet H, or in other words, these two magnets are connected in multiple across the terminals of battery D. Motor M is also energized through a circuit which passes from battery D, through wires 14 and 54, front point of contact 15, wires 19 and 19^a, contact 20, wires 21 and 26, contact 22, wire 25, motor M, and wire 18 to battery D. The motor M then again drives the chains 6 and 6^a of Fig. 1, and inasmuch as magnet H^a is energized, the arm A^a is raised to its elevated position. This operation of arm A^a causes semaphore S to be moved from its caution or inclined position to its vertical or proceed position. When the proceed position is reached contact 22 opens, thereby stopping the motor.

When the signal reaches the proceed position, contact F closes, thereby closing the following circuit for relay L: from battery 53, through pole-changer P^a, wire 45, contact 44 of track relay T, wires 43 and 42, contact F, wire 47, winding of relay L, wires 46 and 37, track relay contact 36, wire 35, and pole-changer P^a to battery 53. The consequent closing of relay L opens the circuit for relay R at contact 67, so that relay R then opens. The parts of the apparatus then occupy the positions in which they are shown in Fig. 2^a. Referring to this view, it will be seen that the magnets H and H^a are now connected in series across the terminals of battery D, the circuit being from battery D, through wires 14 and 51, front point of contact 28 of relay L, wire 29, magnet H^a, wire 30, contact 31, wires 32 and 52, back point of contact 15 of relay R, wire 16, magnet H, and wires 17 and 18 to battery D. Inasmuch as magnets H and H^a are now connected in series, it is obvious that the amount of energy consumed by each magnet is only half of the energy which it would consume if the multiple connection of these magnets across the battery had been maintained. Inasmuch as a signal is in the proceed position during the greater proportion of the time that the signal is in service, it will be seen that by means of my invention a considerable saving in the amount of energy required for the operation of the signal is attained.

With the parts in the positions shown in Fig. 2^a, when a car or train enters block section B-C, the opening of track relay T will open the circuit for relay L, and this latter relay will open at contact 28 the circuit last traced for magnets H and H^a, so that semaphore S will drop to the stop position. The parts of the apparatus will then be restored to the positions in which they are shown in Fig. 2.

Referring now to Figs. 3 and 3^a, the apparatus shown herein is the same as that shown in Figs. 2 and 2^a, in so far as concerns the control of relays R and L. In Figs. 3

and 3^a, however, the battery which supplies energy for the operation of the signal is divided into two sections D^a and D^b, and the signal is controlled in such manner that the two battery sections are connected in series across the terminals of each magnet while the signal is being moved, but that the two battery sections are connected in multiple across the terminals of each magnet while the signal is being held in the proceed position.

Referring now particularly to Fig. 3, I will assume that the car or train W in block section B-C moves out of this section into the section next to the right, so that relay R becomes energized in the reverse direction. Magnet H is then supplied with current, the circuit being from the right hand terminal of battery section D^a through wires 14, 55, 56 and 54, front point of relay contact 15, wire 16, magnet H, wires 17, 18^a and 18, battery section D^b, wire 58, back point of relay contact 59, and wire 60 to battery section D^a. It will be noted that the two sections of the operating battery are connected in series across magnet H at this time. The circuit for motor M is from battery section D^a, through wires 14, 55, 56 and 54, contact 15, wires 19, 23 and 61, contact 22, wires 25^a and 25, motor M, wire 18, battery section D^b, wire 58, back point of relay contact 59, and wire 60 to battery section D^a. When the semaphore reaches the caution position, contact 22 opens so that motor M becomes de-energized.

When relay R becomes energized in the opposite direction, due to reversal of pole-changer P^a, magnet H^a is supplied with current through a circuit which passes from battery section D^a, through wires 14, 55, 56 and 54, relay contact 15, wires 19 and 19^a, polarized contact 20, wires 21 and 27, back point of relay contact 28, wire 29, magnet H^a, wire 30, contact 31 (which is then closed), wires 18^a and 18, battery section D^b, wire 58, back point of relay contact 59, and wire 60 to battery section D^a. The circuit for motor M is then from battery section D^a, through front point of relay contact 15, polarized contact 20, wires 21 and 26, circuit controller 24, motor M, battery section D^b, and back point of contact 59, to battery section D^a.

When the semaphore reaches the proceed position, the motor circuit is opened at contact 24. At the same time circuit controller F reverses, so that relay L closes and relay R opens. The parts are then in the positions shown in Fig. 3^a, wherein it will be seen that the two battery sections are connected in multiple across the terminals of magnet H and also across the terminals of magnet H^a. First considering magnet H, the portion of the circuit which includes battery section D^a passes from the right hand terminal of this section, through wires 14, 55, 56 and 56^a, contact 84 of relay L, wires 130

23, 19 and 16, magnet H, wires 17, 18^a, 18 and 62, front point of contact 63 of relay L, and wires 64 and 69 to the left-hand terminal of battery section D^a. The right hand terminal of battery section D^b is connected with wire 55, through wire 58, front point of contact 59 of relay L and wire 73. The left hand terminal of battery section D^b is, of course, connected directly with wire 18.

10 Considering now magnet H^a, the circuit which includes battery section D^a passes from the right hand terminal of this section, through wires 14, 55 and 65, front point of contact 28 of relay L, wire 29, magnet H^a, wire 30, circuit controller 31, wires 18^a, 18 and 62, front point of contact 63 of relay L, and wires 64 and 60 to battery section D^a. Battery section D^b is connected in multiple with section D^a in the same manner as set forth above.

15 The operation of the apparatus when a car or train enters block D—C or the section to the right of point C, will be understood from the explanation of the operation of the apparatus shown in Figs. 2 and 2^a under similar conditions.

20 In Figs. 4 and 4^a I have shown an arrangement of apparatus which is a combination of the schemes shown in Figs. 2 and 3. That is, the two battery sections D^a and D^b are connected in series across the terminals of magnet H, and also across the terminals of magnet H^a, while the signal is moving, but when the signal is at rest in the proceed position the two battery sections are connected in multiple across the terminals of magnets H and H^a in series. The control of relays R and L is the same as in Figs. 2 and 3.

25 Referring particularly to Fig. 4, when the car or train which is shown in section B—C passes into the section next to the right, the closing of relay R will cause current to be supplied to magnet H, through a circuit which passes from battery section D^a, through wires 14, 55 and 54, relay contact 15, wire 16, magnet H, wires 17 and 18, battery section D^b, wire 58, back point of relay contact 59, and wire 60 to battery section D^a. The circuit for motor M will be apparent from the explanation given hereinbefore of the apparatus shown in Fig. 3. When the signal reaches the caution position, motor M is de-energized, due to the opening of contact 22. When relay R is reversed, due to the reversal of pole-changer P^a, magnet H^a is supplied with current, the circuit being from battery section D^a, through wires 14, 55 and 54, relay contact 15, wires 19 and 19^a, polarized contact 20, wires 21 and 27, back point of relay contact 28, wire 29, magnet H^a, wire 30, circuit controller 31, wire 32, wire 69, back point of relay contact 70, wire 71, battery section D^b, wire 58, back point of relay contact 59, and

wire 60 to battery section D^a. The circuit for motor M is then from battery section D^a, through front point of relay contact 15, polarized contact 20, circuit controller 24, motor M, battery section D^b and back point of relay contact 59 to battery section D^a. When the signal reaches the proceed position the motor is de-energized by the opening of circuit controller 24, and at the same time circuit controller F closes so that relay L closes and relay R opens. The parts are then in the positions in which they are shown in Fig. 4^a. Referring to this view, the circuit for magnets H and H^a, in so far as battery section D^a is concerned, is from the right hand terminal of this section, through wires 14, 55 and 65, front point of relay contact 28, wire 29, magnet H^a, wire 30, circuit controller 31, wires 32 and 72, back point of relay contact 15, wire 16, magnet H, wires 17, 18 and 71, front point of relay contact 70, and wire 60 to battery section D^a. Battery section D^b is connected in this circuit in multiple with section D^a, the left hand terminal of section D^b being connected with the left hand terminal of section D^a, through wire 71, front point of relay contact 70 and wire 60; and the right hand terminal of section D^b being connected with the right hand terminal of section D^a through wire 58, front point of relay contact 59, and wires 73 and 14.

30 The operation of the apparatus shown in Figs. 4 and 4^a when a car or train enters block section B—C or the section to the right will be understood from the explanation of the apparatus shown in Figs. 2 and 3 under similar conditions.

35 Referring now to Fig. 5, the signal mechanism here shown comprises one operating arm A^b, which arm is directly connected with semaphore S. The arm A^b is raised from its lowest position to an intermediate position by chain 6, and from the intermediate to its highest position by a chain 6^a, both of which chains are operated by motor M. Arm A^b is held in its intermediate position by the engagement of shoulder 9 on fork 8 with a latch 85, and in its highest position by the engagement of the same shoulder 9 with a latch 10. Semaphore S, of course, is in the stop, caution or proceed position according as arm A^b is in the lowest, intermediate or highest position. The fork 8 is controlled by magnet 11 in the same manner as in Fig. 1.

40 Referring now to Figs. 6 and 6^a, I have here shown one arrangement of circuits and apparatus for the control of the signal mechanism shown in Fig. 5. Considering first Fig. 6, I will assume that the car or train which is shown in block section B—C passes out of this section into the section next to the right, so that relay R becomes energized in such direction that its polarized

contact 20 is open. Magnet H then becomes energized, the circuit being from battery section D^a through wires 14, 55 and 54, front point of relay contact 15, wires 75 and 76, 5 contact 77-79 of circuit controller G, wire 80, magnet H, wires 17 and 18, battery section D^b, wire 58, back point of relay contact 59, and wire 60 to battery section D^a. The circuit for motor M, briefly traced, is from 10 battery section D^a, through front point of relay contact 15, contact 86-87 of circuit controller K, motor M, battery section D^b, and back point of relay contact 59 to battery section D^a. When the semaphore reaches 15 the caution position, contact finger 87 of circuit controller K is reversed, thereby de-energizing the motor due to the opening of contact 86-87. At the same time, circuit controller G is moved to such position that 20 contact 79-83 is closed but contact 77-79 is not opened.

When relay R reverses, due to the reversal of pole-changer P^a, magnet H is energized through the following circuit—from 25 battery D^a, through wires 14, 55 and 54, front point of relay contact 15, wire 19, polarized contact 20, wires 21 and 27, back point of relay contact 28, wire 29, contact 30 83-79 of circuit controller G, wire 80, magnet H, wires 17 and 18, battery section D^b, wire 58, back point of relay contact 59, and wire 60 to battery section D^a. The motor circuit, briefly traced, is from battery section D^a, through relay contacts 15 and 20, 35 contact 82-87 of circuit controller K, motor M, battery section D^b, back point of relay contact 59 to battery section D^a. When the signal reaches the proceed position, circuit controller F reverses, thereby energizing 40 relay L and de-energizing relay R, so that the circuit for motor M is opened at contact 15 of relay R. The parts then occupy the positions in which they are shown in Fig. 6^a, from which it will be seen that the circuit 45 for magnet H in so far as battery section D^a is concerned, is from the right hand terminal of this section, through wires 14 and 55, front point of relay contact 28, wire 29, contact 83-79, wire 80, magnet H, wires 50 17, 18, 71 and 71^a, front point of relay contact 70, and wires 60^a and 60 to battery section D^a. Battery section D^b is included in multiple with section D^a in this circuit, the connection between the right hand terminals 55 of the battery sections being through wire 58, front point of relay contact 59, and wire 14; whereas the connection between the left-hand terminals of the two battery sections is through wires 71 and 71^a, front point of 60 relay contact 70, and wires 60^a and 60.

It will be seen, therefore, that in Figs. 6 and 6^a the two battery sections are connected in series across the terminals of magnet H at all times when this magnet is functioning, except when the signal is being held

in the proceed position, at which time the two battery sections are connected in multiple across the terminals of magnet H.

Although I have herein shown and described only certain forms of apparatus embodying my invention, it is understood that various changes and modifications may be made therein within the scope of the appended claims without departing from the spirit and scope of my invention. 75

Having thus described my invention, what I claim is:

1. In combination, a signal mechanism comprising two arms biased to lower positions, a motor for moving each arm to an 80 elevated position, means including a magnet for each arm for operatively connecting the arm with the motor and for holding the arm in the elevated position; a source of current; means for connecting said magnets in series 85 across said source when both arms are elevated, and for connecting each magnet directly across said source at all other times when the magnet is functioning; and signaling means controlled by said arms. 90

2. In combination, a signal mechanism comprising two arms biased to lower positions, a motor for moving each arm to an elevated position, means including a magnet for each arm for operatively connecting the arm with the motor and for holding the arm in the elevated position; signaling means controlled by said arms and indicating stop, caution or proceed according as both arms are lowered, one arm is elevated 100 or both arms are elevated; a source of current; and means for connecting the two magnets in series across said source while the signaling means indicates proceed, and for connecting each magnet directly across 105 said source at all other times when the magnet is functioning.

3. In combination, a signal mechanism comprising two arms biased to lower positions, a motor for moving each arm to an elevated position, means including a magnet for each arm for operatively connecting the arm with the motor and for holding the arm in the elevated position; a source of current, a polarized line relay and a local 110 relay for controlling said mechanism, a line circuit which at times includes said line relay but not said local relay, means controlled by said arms when both are in elevated position for disconnecting said line 120 relay from said line circuit and connecting said local relay with said circuit, means for connecting one magnet directly across said source of current when the line relay is energized in one direction and for connecting each magnet directly across said source when the line relay is energized in the other direction and for connecting said two magnets in series across said source when the line relay is de-energized and the local relay 125 130

is energized, and signaling means controlled by said arms.

4. In combination, a signal mechanism comprising two arms biased to lower positions, a motor for moving each arm to an elevated position, means including a magnet for each arm for operatively connecting the arm with the motor and for holding the arm in the elevated position; two sources of current, means for connecting said two sources in series to supply each magnet while the corresponding arm is being elevated by the motor, and for connecting said two sources in multiple to supply each magnet when both arms are in elevated position, and signaling means controlled by said arms.

5. In combination, a signal mechanism comprising two arms biased to lower positions, a motor for moving each arm to an elevated position, means including a magnet for each arm for operatively connecting the arm with the motor and for holding the arm in the elevated position; two sources of current, means for connecting said two sources in multiple to supply each magnet while both arms are elevated and for connecting the two sources in series to supply each magnet at all other times when the magnet is functioning, and signaling means controlled by said arms.

6. In combination, a signal mechanism comprising two arms biased to lower positions, a motor for moving each arm to an elevated position, means including a magnet for each arm for operatively connecting the arm with the motor and for holding the arm in the elevated position; a polarized line relay and a local relay for controlling said mechanism, a line circuit which at times includes said line relay but not said local relay, means controlled by said arms when both are elevated for disconnecting said line relay from said circuit and connecting said local relay with the circuit, two sources of current; means for connecting said two sources in series across one magnet when the line relay is energized in one direction, for connecting said two sources in series across both magnets when the line relay is energized in the other direction, and for connecting the two sources in multiple across each magnet when the line relay is de-energized and the local relay is energized; and signaling means controlled by said arms.

7. In combination, a signal mechanism comprising an arm biased to a lower position, a motor for moving said arm to an elevated position, means including a magnet for operatively connecting said arm with the motor and for holding the arm in the elevated position, signaling means controlled by said arm, two sources of current, and means for connecting said two sources in series to supply said magnet while the

arm is being moved to the elevated position and for connecting said two sources in multiple to supply said magnet while the arm is being held in the elevated position.

8. In combination, a signal biased to one position, a motor for moving it to another position in opposition to the biasing force, a magnet for connecting said signal with said motor and for holding the signal in the position to which it has been moved by the motor, two sources of current, and means for connecting said sources in series to supply said magnet with current while the motor is moving the signal, and for connecting said sources in multiple to supply said magnet with current while the signal is being held in the position to which it is moved by the motor.

9. In combination, a signal mechanism comprising an arm biased to a lower position, a motor for moving said arm to an elevated position, means including a magnet for operatively connecting said arm with the motor and for holding the arm in the elevated position, signaling means controlled by said arm, a polarized line relay and a local relay for controlling said mechanism, a line circuit which at times includes said line relay but not said local relay, means controlled by said arm when elevated for disconnecting said line relay from and connecting said local relay with said line circuit, two sources of current; and means for connecting said two sources in series to supply said magnet when the line relay is energized and the local relay de-energized, and for connecting said sources in multiple to supply said magnet when the line relay is de-energized and the local relay is energized.

10. In combination, a signal biased to stop position, a motor for moving said signal to caution and proceed positions in opposition to the biasing force, means including two magnets for connecting said motor with said signal and for holding the signal in caution and proceed positions, a source of current, and means for connecting said two magnets in series across said source while the signal is being held in the proceed position and for connecting each magnet separately with the source at all other times when the magnet is functioning.

11. In combination, a signal biased to stop position, a motor for moving said signal to caution and proceed positions in opposition to the biasing force, means including two magnets for connecting said motor with said signal and for holding the signal in caution and proceed positions, two sources of current, and means for connecting said two magnets in series across the two sources in multiple while the signal is being held in the proceed position and for connecting each magnet separately across the two sources in

series at all other times when the magnet is functioning.

12. In combination, a signal biased to stop position, a motor for moving said signal to caution and proceed positions in opposition to the biasing force, means including two magnets for connecting said motor with said signal and for holding the signal in caution and proceed positions, two sources of current, and means for connecting said two sources in multiple to supply current to said magnets while the signal is being held in the proceed position and for connecting said two sources in series to supply said magnets with current at all other times when the magnets are functioning.

13. In combination, a signal biased to stop position and a motor for moving it to caution and proceed positions, two magnets, means for holding said signal in caution position when one of said magnets is energized and in proceed position when both magnets are energized, a source of current, and means for connecting said two magnets in series

across said source while the signal is being held in proceed position and for connecting each magnet separately with the source at all other times when the magnet is functioning.

14. In combination, a signal biased to stop position and a motor for moving it to caution and proceed positions, two magnets, means for holding said signal in caution position when one of said magnets is energized and in proceed position when both magnets are energized, and means for applying a relatively low voltage to each magnet while the signal is being held in the proceed position and a relatively high voltage to each magnet at all other times when the magnet is functioning.

In testimony whereof I affix my signature in presence of two witnesses.

RONALD A. McCANN.

Witnesses:

A. HERMAN WEGNER,
E. P. CRUM.
